United States Patent Office.

ROBERT R. SPEEDDEN AND E. CLIFFORD SPEEDDEN, OF ASTORIA
OREGON.

Letters Patent No. 94,660, dated September 7, 1869.

IMPROVED DEVICE FOR PUMPING BY THE MOTION OF THE OARS.

The Schedule referred to in these Letters Patent and making part of the same.

To all whom it may concern:

Be it known that we, ROBERT R. SPEEDDEN and E. CLIFFORD SPEEDDEN, of Astoria, in the county of Clatsop, and State of Oregon, have invented a new and improved Device for Pumping by the Motion of the Oars; and we do hereby declare that the following is a full, clear, and exact description thereof, which will enable others skilled in the art to make and use the same, reference being had to the accompanying drawing, forming part of this specification.

The drawing represents a side view of an apparatus adapted to pump by the motion of the oars.

This invention has for its object to pump a boat by the motion communicated to the oars in the operation of rowing.

One means of carrying this into effect is shown in the accompanying drawing, although suitable other means may be employed for the same purpose.

The pump to be used may be of any suitable construction, and its stroke greater or less, according to the size of the boat; perhaps in no case more than four inches, and as little, in some, as two.

On ships' boats, surf-boats, and, indeed, on all boats so exposed as to be liable to ship water, in most instances when the sea is rough enough to cause a boat to ship water, it is impossible to bail her, as it requires all hands at the oars, and if loaded with people, as in case of wreck, or other marine disaster, there is no possible chance to bail.

The apparatus is so constructed that the pumping-connection can be locked or thrown out of gear when there is no necessity for pumping.

The invention consists chiefly in arranging a sliding row-lock, which will be moved back and forth on the gunwale of the boat, whenever the oar is used, and which by such motion will operate, by suitable connection, a pump for discharging water from the boat.

The invention consists also of the particular apparatus which we represent as one mode of carrying our main invention into effect.

A, in the drawing, represents the side of a boat.

B is the gunwale of the same.

C is the row-lock.

The same projects from a plate, D, which is fitted between ears g g, that project from a plate, E, fastened to the gunwale, so that said plate D can move backward and forward with the row-lock on the fixed plate E.

From the under side of the plate D projects, through a slot of the gunwale, a pin, a, which is fastened to the piston-rod b of a pump, F, as shown.

The pump F is arranged in a suitable part of the

boat, and has a suction-pipe, c, reaching to the bottom of the boat, and a discharge-pipe, d, extending through the side of the same.

A spring, e, is fastened to the pin a, which, when compressed, will push the said pin toward the pump.

The object of this spring is not only to return the pump-piston, after it has been drawn out by the power applied to the oar, but also to so resist the sliding motion of the plate D that the oar in the row-lock will bear with its full force on the water, whilst the row-lock is being forced forward by the power applied by the oarsman.

It will be readily understood that the row-lock will, when the oar is worked in it, be moved forward, to give one stroke of the piston, and that the spring will, when thus compressed, force the row-lock back again, and produce the other stroke of the piston, while the oar is swung back out of water.

A plate, f, is hinged in front of the plate D, to the gunwale, and can be swung down, as shown by red lines in the drawing, when it is desired to lock the said plate, to stop the pumping-operation.

Instead of this plate f, a simple pin, fitted through the gunwale in front of the plate D, or any other equivalent device, may be used.

We do not confine ourselves to the particular apparatus herein described, for utilizing the motion of the oars to empty the boat of its water; but

We do claim as new, and desire to secure by Letters Patent—

1. A sliding row-lock, connected with a pumping-apparatus, so that it may, during the operation of rowing, serve to operate the pumping-apparatus, substantially as herein shown and described.

2. The row-lock C, when fastened to a sliding plate, D, which is, by a pin, a, connected with the piston-rod of a pump, substantially as herein shown and described, to operate as set forth.

3. The spring e, when connected with the sliding row-lock, for the purpose of partly counteracting the forward motion of the row-lock, and for returning the pump-piston, substantially as herein shown and described.

4. The hinged plate f, or its equivalent, when arranged to lock the sliding row-lock, substantially as herein shown and described, for the purpose of arresting the pumping-operation, as specified.

ROBERT R. SPEEDDEN.
